G. H. WILSON

TOBACCO PIPE

Filed Nov. 20, 1925

Inventor
George H. Wilson

By *James L. Dorn*
Attorney

UNITED STATES PATENT OFFICE.

GEORGE H. WILSON, OF LOUISVILLE, KENTUCKY.

TOBACCO PIPE.

Application filed November 20, 1925. Serial No. 70,345.

REISSUED

This invention relates to tobacco pipes and proposes the construction of a pipe in which the stem portion thereof is provided with means for mixing a current or currents of cool air with the heated smoke as it emanates from the smoke passage in the stem, so that excessive salivary secretion incident to the contact of heated smoke with the mouth tissues is avoided, minimizing the tendency 10 to expectorate as well as permitting complete combustion of tobacco into the pipe by avoidance of leakage of saliva back into the stem which occurs when the flow of saliva is unduly stimulated.

15 A further object of the invention is to provide ventilating means for the stem exposed exteriorly thereof so as to be accessible at all times for cleansing or sterilizing.

Other objects of the invention will appear 20 as the following description of a preferred embodiment thereof proceeds.

In the drawings:—

Figure 1 is a perspective view of a pipe incorporating the distinctive features of my 25 invention.

Figure 2 is a plan view showing the stem or mouth-piece.

Figure 3 is a cross section taken along the line 3—3 of Figure 2.

30 Referring now in detail to the several figures, the stem 1 is provided with the superficial grooves 2, which may be one or more in number, and extend preferably but not necessarily, longitudinally of the stem.

35 The grooves are of such narrowness in width as to prevent the lip inadvertently sinking thereinto and occluding the passage of air into the mouth, while at the same time permitting the lip to be used as a valve, when

40 desired, for closing said passages when applying forced draft to the pipe. The lower side of the stem is made without grooves so as to avoid the risk of saliva leaking along the stem, as well as to insure control of the

45 passages solely by the upper lip, and they terminate at the inner end of the stem adjacent the smoke passage 3.

When smoke is drawn into the mouth a

stream or streams of air at atmospheric temperature are simultaneously drawn in 50 through the grooves 2, mixing with the smoke and reducing the temperature thereof, greatly enhancing the pleasure of smoking.

While the effect of a cool smoke is primarily physiological in that it does not excite an excessive flow of saliva, yet it re-acts to the benefit of the pipe in that saliva does not leak down into the stem, impairing perfect combustion of the tobacco, as happens 60 when the saliva flow is stimulated. Furthermore, perfect combustion retards the fouling of the pipe so that a deliciously cool mellow smoke may be enjoyed for a long time, this being made possible either directly 65 or indirectly by the presence of the grooves 2.

The arrangement of the ventilating grooves on the outside of the pipe stem is one of the distinctive features of the invention 70 since it prevents the grooves becoming obstructed by foreign matter, and renders them accessible to mechanical cleansing means as well as to washing and other means of cleansing or sterilization.

75 While I have above described what I believe to be an appropriate and practical embodiment of my invention yet it is to be understood that the utilization of construction hereinbefore described and illustrated 80 need not be adhered to in practice, except in so far as they are prescribed by the expressed terms of the appended claim.

Having described my invention what I claim as new and desire to secure by Letters 85 Patent, is:—

In a tobacco pipe, a stem having an external groove or grooves on the upper side only extending longitudinally of said stem from a point exposed to atmosphere when 90 the pipe is in use to a point adjacent the orifice of the smoke passage.

In testimony whereof I have hereunto set my hand.

GEORGE H. WILSON.
